UNITED STATES PATENT OFFICE

PETRUS E. LEUPEN, OF AMSTERDAM, NETHERLANDS, ASSIGNOR TO NEDERLANDSCHE DOK-MAATSCHAPPIJ N. V., OF AMSTERDAM, NETHERLANDS, A COMPANY OF THE NETHERLANDS

DOCK-STRUT OR STAY

Application filed May 28, 1930, Serial No. 456,667, and in the Netherlands June 1, 1929.

The use of wooden dock-struts or dock-stays causes considerable expenses, primarily because it is necessary to keep a large stock with a view to the necessity of disposing of a great variety of lengths. Furthermore, the struts must often be renewed, because of their heads putrefying, whereas the transport of the stays to and from the storehouse takes up much time.

10 In accordance with the invention, the dock-strut is of iron and telescoping, so that it can be adjusted to the required length in accordance with the width of the vessel to be docked. This adjustment is preferably effected by means of a cross-pin cooperating with holes, of which each strut part is provided, the pitch of the holes in the one part being, however, different from that in the other part, so that, notwithstanding the considerable distance that must be necessarily be left between adjacent holes, a fine adjustment of the total length of the stay can be obtained.

15 The tubular or outer part of the stay is preferably provided with a series of eyes, or with a section iron rivetted thereto and having a series of holes, or with a plurality of such section irons, or with a strap having a hook or an eye and adapted to be clamped in the required position to said outer part, or 20 with any other suitable element allowing the stay to be engaged by the rope of a crane so as to assume a substantially horizontal position when freely suspended. It will be understood that the centre of gravity of the stay

25 will be shifted when the length of the stay is varied. As it is desired to keep the stay in a substantially horizontal position, it is necessary to engage it vertically above its centre of gravity. By the provision of a plurality of eyes for the engagement of the load hook of the crane, or for the provision of D-shackles, it is possible to determine, for each adjusted length of the stay, the suitable point 30 where the stay should be engaged by the load hook, so that the stay will be in equilibrium when being hoisted.

35 One end of the stay may be provided with a screw jack, so as to avoid the necessity of using wedges.

The drawings illustrate, by way of example, two embodiments of the invention.

Fig. 1 is a side elevational view of the stay having its minimum length, and

Fig. 2 is a plan view thereof.

Fig. 3 shows the stay having its maximum length, the outer end of the inner part being broken away and the end of the outer part being provided with a screw jack.

Fig. 4 is a cross-section along the line IV—IV in Fig. 3, on an enlarged scale.

Fig. 5 illustrates how the novel dock-stays are used.

The outer part of the dock-stay extends from *a* to *b*, the inner part from *c* to *d*.

45 The outer part essentially comprises two channels 6 interconnected by strips 7, U-irons 8 and angles 9, so that its inner walls are entirely smooth. Secured to it at the end *b* (Figs. 1 and 2) is a wooden block 10 adapted to be engaged by wedges 11, when the stay is in operation.

50 The inner part *c*—*d* essentially consists of two channel irons 12 arranged with their flanges towards one another. Rivetted to the inner faces of the flanges are the fish plates 13. The rivets are countersunk in the beams 12, so that the inner part has smooth outer walls from *c* to *d*. At the end *d*, the beams are bent inward, whereby the introduction of part *c*—*d* into the part *a*—*b* is facilitated. The beams 6 may be normal sections. The beams 12 should have a slightly lower section to prevent them from jamming in the outer part. Said beams may suitably be bent from strips. At the end *c*, a head 14 is pivoted to the inner part by means of a pin 15, so that the wooden bearing block 16 can adjust itself to the ship's side.

55 To the angle 17 is secured a D-shackle 18 adapted to be engaged by a steel rope 19, by which the stay can be suspended from the ship (see Fig. 5).

The flanges of the channels 6 of the outer part are provided with series of registering holes 20. At the end *d* of the inner part, there are only two pairs of holes 21 spaced apart a distance equal to one half of the pitch of the holes 20. A cross connecting pin 22 is adapted to be passed through the holes 20 and

21. By providing the part *c-d* with say four sets of holes spaced apart at unequal distances all smaller than the pitch of holes 20, it is possible to still more accurately adjust the length of the stay.

5 Riveted to the outer part are two angles 23 having a series of holes 24 therein. These holes are adapted to receive D-shackles 25 for fastening a strap adapted to be engaged by 10 the load hook of the crane. If the stay has its minimum length, it will, when being suspended from the crane, assume a horizontal position if the D-shackles 25 engage the holes 24 to the extreme right, see Figs. 1 and 2. If 15 the stay has its maximum length, (Fig. 3), the D-shackles 25 should engage the holes 24 to the extreme left in order that the stay be horizontal when suspended (Fig. 3). By placing the one D-shackle 25 in one hole of the 20 one angle 23 and the second D-shackle in the next hole of the other angle 23, the point of engagement by the load hook may be varied by a length equal to only one half of the pitch of holes 24, although it does not matter 25 very much whether the stay, freely suspended from the crane, assumes a somewhat inclined position, because the rope 19 allows of the correct position to be easily obtained.

30 In accordance with Fig. 3, the block 3 is secured to the head of a screw jack 27, the nut of which is adapted to be rotated by means of a ratchet 29, whereby the same effect can be obtained as with the wedges 11.

35 Tubular dock stays in accordance with the invention can be made to afford great strength and are more reliable than are wooden struts. It is, therefore, possible to hold a vessel in equilibrium with a relatively small number of iron stays. The positioning and 40 the removal of the stays takes, therefore, very little time and when the vessel is to be repaired, said stays are not so in a man's way than are the great number of wooden stays that would otherwise have to be used.

45 What I claim is:—

An adjustable multi-part dock stay, one part being adapted for sliding movement within another part, a cross-pin interconnecting both parts, and at least one bar connected 50 to the second part, the said bar being provided with a number of hoisting-holes, the first and the last hole of which are situated near the centres of gravity of the dock stay when it is adjusted respectively to its minimum length and to its maximum length.

In testimony whereof I affix my signature.
PETRUS E. LEUPEN.
